UNITED STATES PATENT OFFICE.

FRED B. CARLISLE, OF NORTH KINGSTON, RHODE ISLAND, ASSIGNOR TO JOSEPH M. GILBERT, OF NEW YORK, N. Y.

DESIGN FOR A TIRE-TREAD.

50,931.

Specification for Design. Patented June 19, 1917.

Application filed November 13, 1916. Serial No. 131,153. Term of patent 14 years.

To all whom it may concern:

Be it known that I, FRED B. CARLISLE, a citizen of the United States, and a resident of North Kingston, county of Washington, State of Rhode Island, have invented a new, original, and ornamental Design for Tire-Treads, of which the following is a specification.

Reference is to be had to the accompanying drawings in which Figure 1 represents a face view of a portion of a tire including my new design, and Fig. 2 is a sectional view on the line 2—2 of Fig. 1.

The design comprises a zigzag groove having the appearance of a flash of lightning as the latter is customarily illustrated which groove is formed in the tread of the tire so as to extend circumferentially thereof. In the illustrated example shown in the drawing, a pair of such grooves are arranged in parallel relation to each other upon the tire tread.

I claim:

The ornamental design for a tire tread as shown and described.

FRED B. CARLISLE.
